UNITED STATES PATENT OFFICE.

HERMAN HOLLERITH, OF NEW YORK, N. Y.

ELECTRO-PNEUMATIC BRAKE FOR RAILROAD-TRAINS.

SPECIFICATION forming part of Letters Patent No. 363,464, dated May 24, 1887.

Original application filed November 1, 1886, Serial No. 217,708. Divided and this application filed April 16, 1887. Serial No. 235,091. (No model.)

To all whom it may concern:

Be it known that I, HERMAN HOLLERITH, of New York, in the county of New York and State of New York, have invented certain new and useful Improvements in Pneumatic Brakes for Railroad-Trains; and I do hereby declare the following to be a full, clear, and exact description of the same, reference being had to the accompanying drawings, forming a part of this specification, and to the figures and letters of reference marked thereon.

This invention relates to that class of pneumatic brakes which are applied or set by the opening of communication between the external air and a main pipe extending through the train, of which class the Westinghouse, Carpenter, and Eames automatic brakes, for example, are types. Ordinarily this opening of communication between the main pipe and external air is effected at but one point only—namely, at the engine—and an appreciable amount of time is required to fully exhaust or fill the main pipe, from which it results that the brakes on the car nearest the engine are most quickly acted upon, while those on the other cars are operated upon more or less tardily, according to their degree of remoteness from the engine.

Where a train is made up of but few cars the difference in point of time in which the brakes of the several cars go on and off is of slight consequence; but where long trains are employed this difference is found to be so great as to cause the cars in the fore part of the train to be fully braked before the last cars are materially affected, thereby producing such collision and shock between the parts of the train as to do serious damage. Especially is this the case where a quick or emergency stop is attempted to be made.

In an application for Letters Patent filed by me on the 1st day of November, 1886, Serial No. 217,708, I have shown and described a method of remedying the difficulties above alluded to, such method consisting in opening communication between the main pipe and the external air at two or more places simultaneously, so as to cause all the brakes throughout the train to be operated more nearly simultaneously, the instrumentalities employed

being preferably a series of valves located in the main pipe at different points and operated electrically by the engineer from the engine.

The improvements which I desire to cover herein relate to special devices for carrying my said improved method into practice. I will first describe them and then point out their peculiar features of novelty in the claims at the end of this specification.

Referring to the accompanying drawings, Figure 1 represents a train of cars, showing the application of my invention; Fig. 2, a side view of one of the valve-boxes; Fig. 3, a top view; Fig. 4, a vertical sectional view of the same; Fig. 5, a view of a modified form of valve-easing.

Similar letters of reference in the several figures indicate the same parts.

A represents the main pipe of any ordinary automatic pneumatic-brake system; B, the lever by which the engineer controls the admission of pressure to or the lowering of pressure in the said main pipe, as usual.

C is a valve-box, consisting, preferably, of a casing having at its opposite sides half-couplings D D', adapted to co-operate with the ordinary couplings, E E, on the air pipe A at the ends of each car, as shown. Within this box is arranged an electro-magnet, F, having a hinged armature, G, which bears a disk, d, of suitable material, to serve as a valve for closing a tubular valve-seat, V, leading to the atmosphere. One of the terminal wires, g, of the magnet F is electrically connected to the half-coupling D and the other wire to the half-coupling D', and the half-couplings are insulated from each other in any suitable manner, such as by placing insulating material between one of them and the casing C, or by making the casing itself in two sections and applying insulation between the sections, as shown in Fig. 5 at i.

The couplings E E on the cars form part of an electric circuit, T, that extends through the train, and is preferably adapted to be broken or made by the co-operation of the engineer's lever B with a contact, H, as shown in Fig. 1.

It will be apparent that when the valve-box C is connected to the couplings E E at the ends of adjoining cars it serves both to estab-

lish the continuity of the main pressure-pipe A and to complete the electric circuit and include the magnet F therein, so that when the engineer turns his lever B to open communication between the main pipe and the external air at the engine, in the usual manner, he also completes the electric circuit by bringing said lever against the contact H, thereby causing the magnet F to be energized, the armature G attracted, and the tubular valve-seat V uncovered, so as to open an additional channel of communication with the atmosphere, and thus render the action of the brakes more uniform.

15 Of course the greater the number of valve-boxes C employed the more nearly simultaneously will all the brakes be applied. In practice it will be found necessary to employ but few of them in a comparatively long train, 20 though, if desired, one can be coupled to the air-pipes between every two adjoining cars.

I preferably make the valve-boxes as light as is consistent with the proper degree of strength and provide them with couplings corresponding to those on the pipes of the cars with which they are to be used, thereby enabling them to be applied or removed with the greatest facility by any ordinary train-hand.

I do not of course limit myself to any particular construction of valve-box, magnets, valves, or valve seats, as these parts may be varied indefinitely in form and construction.

The electric circuit may be arranged entirely upon the train or grounded at the ends thereof, 35 as desired, and the means for making and breaking the circuit at the engine may be entirely disconnected from the lever by which the engineer controls the pressure in the main pipe, as will be readily understood.

40 I do not claim herein the combination, with the main valve on the engine by means of which

the pressure in the main pipe is controlled by the engineer, of separate electrically-operated valves on the several cars for controlling communication between the main pipe and the atmosphere and rendered operative by the movements of a switch connected to the said engineer's pressure-valve, as such subject-matter is covered by my said original application No. 217,708, of which this is a division; nor do I claim herein, broadly, the combination, with a brake system such as described, of a valve-box adapted for connection with the main pipes and electric circuits otherwise than by detachable couplings operating substantially 55 in the manner herein described, as such subject is broadly covered in another division of my original application Serial No. 217,708, which I am about to file.

Having thus described my invention, what I claim as new is—

1. In a brake system such as described, the combination, with the main pipes and couplings thereon, of a valve box or casing having couplings for co operating with the couplings 65 of said main pipes, and containing a valve for controlling communication with the atmosphere, substantially as described.

2. In a brake system such as described, the combination, with the main pipes and couplings thereon and an electric circuit, of a valve box or casing having couplings for co operating with the couplings on said main pipes, and containing an electro-magnet and a valve operated thereby for controlling communication 70 with the atmosphere, substantially as described.

HERMAN HOLLERITH.
